(57) **CLAIM**

The ornamental design for radiocommunication equipment,
as shown and described.

DESCRIPTION

FIG. 1 is a front view of the radiocommunication equipment
according to the present invention.

FIG. 2 is a perspective view of the radiocommunication equipment
according to present invention as seen from the
front, top and right side thereof.

FIG. 3 is a top view of the radiocommunication equipment
according to the present invention.

FIG. 4 is a bottom view of the radiocommunication equipment
according to the present invention; and,

FIG. 5 is a left side view of the radiocommunication equipment
according to the present invention.

The broken lines, which define the bounds of the claimed
design, form no part thereof. The broken lines are for
illustrative purpose only and form no part of the claimed
design.

1 Claim, 5 Drawing Sheets

FIG. 1

FIG. 3

FIG. 4

FIG. 5

UNITED STATES PATENT AND TRADEMARK OFFICE
CERTIFICATE OF CORRECTION

PATENT NO. : Des. 531,983 S
APPLICATION NO. : 29/236155
DATED : November 14, 2006
INVENTOR(S) : Yasushi Akita
